United States Patent

Des. 235,815
Patented July 8, 1975

235,815

PERMANENT WAVE HEATING MACHINE

John R. Forsberg, Arlington Heights, Ill., and Edward H. Meisner, Wyckoff, N.J., assignors to Helene Curtis Industries, Inc.

Filed July 25, 1973, Ser. No. 382,360

Term of patent 14 years

Int. Cl. D28—03

U.S. Cl. D86—10 E

FIG. 1

FIG. 2

FIG. 3

FIG. 4

FIG. 1 is a front view of a permanent wave heating machine showing our new design;

FIG. 2 is a top front perspective view thereof;

FIG. 3 is a top rear perspective view thereof; and

FIG. 4 is a side elevational view thereof.

We claim:

The ornamental design for a permanent wave heating machine, as shown.
